CAR SEAL

George G. Canter, New York, N. Y.

Application December 26, 1951, Serial No. 263,349

2 Claims. (Cl. 292—323)

This invention relates to seals, more particularly to that type generally designated as "car seals" which are used to protect goods in transit in freight cars, trucks and various other kinds of locked containers.

In the making of car seals, which are destroyed after a single use, cost is a very important factor since to meet competitive conditions and satisfy purchasers they must be sold at the present time, for less than a cent a piece. At the same time, no sacrifice in the degree of protection afforded by the seal is permissible.

The general object of the present invention is to provide a seal affording as much protection as any now available, which can be manufactured very inexpensively on fully automatic machinery by stamping and bending operations without necessitating any hand assembly, which is formed entirely of sheet metal and which may be made in one piece.

The invention will best be understood from the following description of the present preferred embodiment thereof, taken in conjunction with the drawings in which:

Fig. 1 is a plan of the flat blank from which the seal is made before any forming operations have been performed thereon in its actual size in the original drawings;

Fig. 2 is a similar view on an enlarged scale showing the upper end of the blank partially formed;

Fig. 3 is a section taken on the line 3—3 of Fig. 2;

Fig. 4 is a section taken on the line 4—4 of Fig. 2;

Fig. 5 shows the locking tongue folded over onto the top half of the seal;

Fig. 6 shows the top half folded over on the bottom half;

Fig. 7 shows the locking end of the seal in completed form;

Fig. 8 is a section on the line 8—8 of Fig. 7;

Fig. 9 is a longitudinal central cross-section on a still larger scale, showing the end of the strap being inserted in the seal before locking takes place;

Fig. 10 is a similar view showing the seal fully locked; and

Fig. 11 is a perspective showing how the seal is used.

Referring to the drawings, the blank of Fig. 1 consists of a single piece of sheet metal having slight springiness, such as quarter hard cold rolled steel about .015" thick, comprising a strap 14, the lower end 15 of which is reduced in width and contains a locking aperture 16, preferably having the outline of the letter B, the straight side of which is directed toward the upper end of the strap. The pointed opposite side aids in the locking function, as hereinafter described. (The terms "upper," "lower" etc. are only relative and used with reference to positions in the drawing merely for convenience.) The hole 18 is provided for stringing the seals in bundles. At the upper end the blank has a terminal portion 19, a seal top section 20 and a seal bottom section 21, hereinafter sometimes referred to as the top and bottom of the seal.

When this blank has been formed and folded it produces without any other parts a complete seal which may be used as illustrated in Fig. 11, where the seal is generally indi-

2

cated at "S," by passing it through a bolt 22 or the like to prevent its removal from a hasp 24 forming part of a conventional lock.

The steps of transforming the blank of Fig. 1 into the completed seal will now be described by reference to Figs. 2 through 8.

In Fig. 2 the outermost end of the terminal portion 19 has been shaped to form the locking tongue 25 which has the curvature of a spoon as may be seen in Figs. 9 and 10. The wings 26 immediately below tongue 25 are bent out of the plane of the blank in the direction of the concave side of the tongue so that this portion of the blank is channel-shaped in cross-section, as may be seen in Figs. 3 and 4. The edges of the top section 20 are bent upwardly and outwardly to produce the sides 28 having outwardly extending flanges 29. The longitudinal edges of the bottom section 21 are turned upwardly to form flanges 30 which are spaced apart by the distance between the outer edges of the flanges 29. Centered roughly two-thirds of the distance from the top edge to the bottom edge of top section 20, this section is depressed to form a dome 31. This dome is shown as having the shape of a segment of a sphere, which is a convenient shape to make but other forms of depression would suffice. In a similar position in the bottom section 21, the metal is pressed upwardly to form a smaller dimple 32. In the segment of the strap between the wings 26 and the top section 20 a narrow rectangular slot 34 is punched, long enough to receive strap end 15.

The terminal portion 19 is next twice bent at right angles on the dotted lines 35 of Fig. 2 so that the section of metal 36 between these lines forms an end for the seal enclosure which contains a portion of the slot 34 which is just slightly wider than the thickness of lower end 15 of the strap. The position of slot 34 in the finished seal may be seen in Figs. 9 and 10. The tip of tongue 25 at this time extends into the dome 31 and above the plane of the inside face of top section 20.

The terminal portion 19 having thus been folded, the top section 20 is next folded over on bottom section 21 by forming two right angle bends on the dotted lines 38 of Fig. 5, so that the section of metal 39 between these lines is formed into another end enclosure and the flanges 29 lie against the inner face of the bottom section 21. The seal now appears as in Fig. 6 and is completed by turning the flanges 30 inwardly, or crimping them, over the flanges 29, after which four short segments of the thus formed edge joints are struck downwardly as shown at 40 (Figs. 7 and 8) to make it more difficult to pry open this joint without leaving clear signs of tampering.

To facilitate the entrance of strap end 15 into the flat rectangular box-like structure thus formed, through the slot 34, the end wall 36 is then dished slightly inwardly as shown at 41 (Figs. 7, 9 and 10). Slot 34 being on the fold line which is adjacent bottom section 21, the strap end will be guided into the slot by sliding it along the face of the strap and, if it encounters the end wall 41, its dished shape will aid in guiding the strap end into the slot 34.

By these simple forming, bending and crimping operations a completed seal is produced from a single flat blank of stock, the finished seal consisting of the elongated strap 14 having integral with its top end a flat rectangular box-like enclosure having a narrow entrance slot adjacent the face of the strap through which the lower end 15 of the strap may be introduced.

After the strap has been passed through a bolt or the like as shown in Fig. 11, the strap end 15 is inserted through the slot 34 and locked irremovably inside of the box. This locking action takes place as follows: Referring to Fig. 9, as the strap end 15 is pushed through slot 34 it is directed upwardly by the concave side or

upwardly sloping face of tongue 25 until it encounters the concave under side of dome 31 along which it slides, by which it is directed downwardly under the seal top 20 at the same time flexing the tongue 25 downwardly far enough to let the strap pass between tongue 25 and top 20. This may tend to bend the end of the strap downwardly slightly. As the strap end is further advanced the flexed tongue springs back to its normal position, in which its end is within the dome 31, as the aperture 16 drops over the end of the tongue. The parts are now in the position shown in Fig. 10 from which it will clearly be seen that it is impossible to withdraw the strap. Any attempt to withdraw it wedges the edge of the strap underneath the convex side of the tongue 25. This will only lift the tip of tongue 25 into contact with the underside of dome 31, beyond which it cannot move. The spoon shape of the tongue makes it very rigid so that its holding power is very great as it cannot be bent backwardly toward opening 34 by pulling on the strap. Neither can the strap be manipulated to get it over the end of the tongue which is above the plane of the inner face of top 20. The point of the B shaped aperture, by engagement with the convex sloping side of tongue 25, tends to bend upwardly the portion of the strap end which is beyond the aperture, helping it to slide down under the tongue.

The shoulders 42 at the junction of strap 14 with its narrower end portion 15 are wider than slot 34 so that the strap can be inserted in the seal only to such a distance as brings the shoulders 42 into engagement with the end wall 36. The distance between the shoulders and aperture 16 is such that the strap can be inserted only far enough to bring about the engagement of this aperture with locking tongue 25.

The dimple 32 is so positioned as to underlie the root portion of the tongue 25 to assure that the tip of the tongue lies within the confines of dome 31. With proper care in the formation of the parts, the dimple 32 may be omitted without detracting from the above described operation. Furthermore, it is not strictly necessary to provide the terminal portion with the wings 26 which merely provide added rigidity to the structure and may be formed at no cost simultaneously with the bending of other parts from metal which would otherwise be waste. It is, therefore, to be understood that these refinements and other details such as the specific shapes of the parts as described, may be omitted or altered without depart-

ing from the spirit of the invention as hereinafter defined in the claims.

What is claimed is:

1. In a seal of the type which comprises a sheet metal strap having a locking aperture near one end, a shallow box having a bottom section integral with the strap at the other end, and a top section joined to said bottom section, said top section having a terminal portion folded downwardly and inwardly to overlie said bottom section within said box, and formed into a tongue extending upwardly from said bottom section toward said top section, the end of said tongue being adapted to snap into said aperture when the end of the strap is inserted into said box; the improvement which resides in said folds in the top section being substantially at right angles and said top section having a slot to receive the strap end which slot is positioned across the fold which is adjacent said bottom section, whereby the strap end may be guided directly into said slot by sliding it along the adjacent portion of the strap.

2. In a seal of the type which comprises a sheet metal strap having a locking aperture near one end, a shallow rectangular box having a bottom section integral with the strap at the other end, and a top section joined to said bottom section, said top section having a terminal portion folded downwardly and inwardly to overlie said bottom section within said box, and formed into a tongue extending upwardly from said bottom section toward said top section, the end of said tongue being adapted to snap into said aperture when the end of the strap is inserted into said box; the improvement which resides in said folds in the top section being substantially at right angles and said top section having a slot to receive the strap end which slot is positioned across the fold which is adjacent said bottom section, the wall of said top section adjacent the slot being dished inwardly to guide the strap end into said slot.
